UNITED STATES PATENT OFFICE.

WALLACE L. COOK, OF CHICAGO, ILLINOIS.

PROTECTOR.

Application filed May 8, 1919. Serial No. 295,651.

To all whom it may concern:

Be it known that I, WALLACE L. COOK, a citizen of the United States, residing at Chicago, in the county of Cook and State 5 of Illinois, have invented a certain new and useful Improvement in Protectors, of which the following is a full, clear, concise, and exact description, reference being had to the accompanying drawings, forming a part 10 of this specification.

My invention relates to protectors and more particularly to protectors of the type known as lightning or high potential arresters. In protectors such as cable 15 protectors, telephone and telegraph protectors, switch-board protectors or the like, the lightning arresters have usually taken the form of two solid conducting blocks of carbon, which are removably connected to the 20 line and ground terminals, respectively of the circuit or apparatus to be protected, these blocks being held apart by an interposed strip of insulation. This strip is 25 cut or perforated so as to provide an open space cut-out for the passage of the discharge from one block to the ground block to thus protect the apparatus to be protected against high potential currents such, for instance, as the direct current five hundred 30 volt trolley current. The incoming wires associated with the protectors and which are the wires that may become charged with the high potential are usually connected to the lightning arresters after 35 having passed through fuses. The open space cut-out above referred to between the blocks is delicately adjusted to break down on five hundred volts direct current so that a discharge may take place, for 40 instance, if one of the line wires become crossed with a trolley circuit. The establishment of the arc across the air gap generally increases current flow so that the fuse is blown thus interrupting the flow of the 45 current through the protectors.

In many cases the air gap above referred to must be no greater than five one-thousandths of an inch. The maintenance of this slight gap presents many difficulties and 50 annoyances. The separators between the arrester blocks are loose and merely held in place by the tension of the springs which hold the blocks. Displacement of these insulators is thus very frequent thereby causing 55 the arrester blocks to become short circuited so as to establish a ground upon the

line. Carbon arrester blocks also have a tendency to dust, and metal blocks to blister on static and other discharges which likewise cause grounds. 60

For the reasons outlined such carbon arresters are continually giving trouble even though no high potential voltages have been upon the line. The troublemen or maintainers who have custody of such devices in 65 actual use are therefore frequently found to increase the number of separators between the discharge blocks so as to avoid these grounds. Such action of course destroys the efficiency of the arrester although 70 it does prevent many accidental grounds. Frequently troublemen or maintainers remove the discharge blocks altogether when they clear a ground so as to avoid future trips to clear grounds whereby the plant or instruments are left without protection 75 against high potential discharges. Protectors of the saw tooth adjustable air gap type as shown in Patent No. 1,122,575, issued to myself and George W. Rodormer, December 29, 1914, avoid most of the objectionable 80 features enumerated above, but are not adaptable to switch-boards and cable protectors or to many other protectors of similar types, because they cannot be mounted 85 in a sufficiently confined space. In protectors which use two solid discharge blocks, the blocks are readily removable; they represent a very small proportion of the cost 90 of the entire protector equipment with which they are associated, but their tendency to cause permanent grounds on the lines destroys not only their efficiency but the efficiency of the entire protector.

My invention contemplates adapting the 95 self-clearing saw tooth or similarly constructed arrester for use in protectors so that it may be mounted upon close centers. In constructing the arresters of my invention, I arrange them of such form that 100 they can be used in existing protector units.

My improved protectors are so designed that they are not subject to the frailties above enumerated in connection with protectors of the prior art and their absence 105 to cause grounds upon the line makes it possible to operate equipment without interruptions to the service and thus greatly improve the efficiency of such protectors. The readily removability of the arresters of 110 my invention increases their effectiveness.

My invention avoids the difficulties as

above outlined in connection with the loose strip of insulation. This loose strip of insulation is usually made of mica, and mica does not lend itself readily for the purpose of manufacturing strips of an exact thickness. The structure of my invention also makes it possible to provide arrester equipment which may operate on a very low voltage break-down.

10 In accordance with my invention, I provide as one element of the arrester a serrated or saw tooth or similar structure which is placed in close proximity to the other element. I find that such a saw tooth or similar element will generally maintain an arc for a sufficient length of time to blow the fuse and will then clear itself. Such a saw tooth or similar element will not become accidentally grounded due to 15 dust particles and the arrangement of my improved structure is such that there is no danger of accidental displacement of the insulation whereby a ground may be occasioned. My improved device furthermore 20 is of such a character that a space is provided between the saw tooth portion and its carrier so dust particles are prevented from settling into a position where they might ground the lines.

25 30 My invention concerns itself also with the provision of a device of this character which is of such construction that the air gap will be maintained to the proper thousandth of an inch as may be required for 35 the particular instruments involved.

I will explain one form which my invention may take more in detail by referring to the accompanying drawings, in which—

Fig. 1 is a side view of one form of protective device in which my improved arrester 40 may find application;

Fig. 2 is a sectional view on line 2—2 of Fig. 1;

Fig. 3 is an enlarged sectional view of the 45 structure shown in Figs. 1 and 2, fragmentary in form to illustrate my improved protector;

Fig. 4 is a perspective view of the insulating mounting of my protector element;

Fig. 5 is a sectional view on line 5—5 of Fig. 3;

Fig. 6 is a side view of the protective element shown in Fig. 5;

Fig. 7 is a sectional view of a punch and die illustrating the manner of forming my improved protective element;

Fig. 8 is a sectional view on line 8—8 of Fig. 7, and

Fig. 9 is a fragmentary longitudinal 60 sectional view of my protector element showing an added feature.

Referring more particularly to Figs. 1 and 2, I show a customary form of pole top cable terminal having a suitable base plate 65 10 to which strips 11, 11 are mounted which

carry protectors, these protectors consisting of the fuses 12 and my improved lightning arresters 13.

The lightning arrester construction of my invention is more clearly illustrated in Figs. 70 3, 4, 5 and 6. In the preferred form as here shown the lightning arrester construction contemplates the use of two arrester elements, one of which is the old and well known carbon ground element 14 which operates in co-operative relation with the other element 15, the element 15 constituting the structure of my invention. The element 15 includes a metallic serrated element 16 preferably U-shaped wherever it is desired to 75 have two serrated edges. The U-shaped element 16 has the two arms 17, 17, the lower edges of which are serrated to form teeth 18, which teeth are the proper distance away from the ground element 14 when the two 80 mates 14 and 15 are in co-operative relation. The element 16 is fixedly mounted upon an insulating base plate 19 shown more clearly in Fig. 4, this base plate 19 having holes 20 into which fingers 21 punched out of the 85 material of the element 16 are forced, to hold the parts 16 and 19 securely together. The edges of the teeth 18 terminate short of the lower line of the insulating base plate 19 so that the proper air gap exists between the 90 teeth 18 and the carbon 14. The material constituting the spark element 16 is sufficiently strong so that it will not be bent under any conceivable force that may be applied to it during its proper use. For 95 this reason the air gap is always of the proper length.

It will be also noted that the legs 17 of the U-shaped element 16 do not hug the sides of the insulating element closely, but that a suitable space 22 is left. This space 100 prevents the accumulation of dust which might cause a grounding or short circuit between the teeth 18 and the carbon block 14. The device is thus self-cleaning in its nature. 105 When the two mates are placed together ready for insertion in the device they are pressed between the two holding springs 23 and 24.

My invention further contemplates the accurate setting of the extremities of the teeth 110 18 relatively to the lower surface of the insulating base plate 19. In manufacturing the device I prefer to fixedly secure the spark element 16 to the insulating base 19 and then place the entire structure between a suitable punch and die which are shown in Fig. 8, the punch being shown at 25 and the die at 26. The die is so arranged that the legs 17 of the elements 16 rest upon little 115 step-like portions 27 elevated the proper amount above the bottom wall 28 of the die. The punch has a resiliently carried movable holding element 29 which first engages the top of the spark element 16 as the punch is 120 125 130

moving downwardly, thus to hold the parts in position. A further downward movement of the punch causes the punch fingers 30 to press against the extremities of the element 16 and thereby to force the insulating base plate 19 downwardly until its lower surface engages the bottom wall 28 of the die. This leaves impressions 31 (Fig. 3), when the fingers have actuated the metallic portion 10 of the element 16. Thus by virtue of these depressions the position of the insulating base 19 relative to the spark element 16 is maintained. Each and every device is thus accurately set so that the base of the 15 teeth 18 are the proper distance backwardly from the base line of the insulating element 19. As before stated, the entire element 15 is sufficiently rigid so that its structure is maintained intact in the course of any 20 ordinary usage. It will of course be apparent that it is immaterial what mate is used in connection with my improved arrester element, the drawings merely showing its connection with the customary carbon element 25 14.

In Fig. 9, I show my improved protector element as provided with a plug of solder 32 which is designed to melt and cause a permanent electrical contact between the finger 21 and the ground plate 14 whenever the arc is continued a sufficient length of time to heat the arrester beyond a predetermined amount. The short circuiting of the elements 21 and 14 will be then a positive assurance that the fuse blows to thereby open the circuit, and protect the apparatus against the high potential.

In the claims I use the words "ground plate" as indicative of any kind or character 40 of mate which may be used in connection with my improved protective element.

It will also be apparent that many modifications may be made from the device as herein disclosed without departing from its 45 spirit. Having however thus described one form which my invention may take, what I claim as new and desire to secure by Letters Patent is:—

1. A high potential protector comprising 50 a ground plate and a cooperating protector device consisting of a U-shaped conducting element and an insulating element secured together and set in permanent relationship so that when said device and plate are juxtaposed with the insulating element abutting said plate, said conducting element and plate form a spark gap of predetermined length between them, the legs of said conducting element being spaced from said insulating 55 element to prevent the accumulation of foreign matter at their active extremities.

2. A high potential protector comprising 60 a ground plate and a co-operating protector device comprising a conducting element, and an interposed insulating element, said

conducting element being provided with a portion adapted to engage said insulating element and having a portion extending substantially at right angles thereto provided with a serrated free edge portion 70 forming a multiplicity of discharge points spaced both laterally and longitudinally from all other portions of said protector.

3. As a new article of manufacture a protector element adapted to co-operate with a ground plate, comprising as a unitary structure, a U shaped conducting element, and an insulating element within said conducting element, the bight portion of said U shaped element being provided with indentations adapted to engage the adjacent face of said insulating element, said indentations being of such proportions relative to the insulating element that said elements are set in definite relationship to provide an air gap of predetermined length between said plate and element, regardless of slight variations in the size of said insulating element.

4. A device of the character described, a 90 removable protector comprising a metallic member having a serrated edge portion, spaced from all portions of said device, a block of conducting material and an insulating element interposed between said block 95 and said metallic member, conducting holding means engaging said block and metallic member on opposite faces of said protector and abutments for preventing lateral shifting of said removable protector relative to 100 said holding means.

5. As a new article of manufacture a 105 readily removable protector element adapted to cooperate with a ground plate, comprising as a unitary structure a conducting element having a serrated active extremity and an insulating element secured to said conducting element, said conducting element being provided with indentations engaging said insulating element whereby the parts 110 are held in definite relationship to establish an air gap of predetermined length between said plate and element when juxtaposed regardless of any variations in the size of said insulating element.

6. As a new article of manufacture a protector element adapted to cooperate with a ground plate, comprising as a unitary structure a conductor element and an insulating element set in definite relationship to establish an air gap of predetermined length between said plate and element when juxtaposed, said insulating element having holes and said conducting element having fingers forced into said holes whereby the two parts 125 are fixedly held together.

7. As a new article of manufacture a protector element adapted to cooperate with a ground plate, comprising as a unitary structure a conducting element and an insulat- 130

ing element set in definite relationship to establish an air gap of predetermined length between said plate and element when juxtaposed, said conducting element at its active 5 extremity being spaced from said insulating element to prevent the accumulation of foreign matter at said active extremity, said insulating element having holes and said conducting element having fingers forced 10 into said holes whereby the two parts are fixedly held together.

8. As a new article of manufacture a protector element adapted to cooperate with a ground plate comprising as a unitary structure a U-shaped conducting element having two serrated active extremities, and an insulating element set in definite relationship by a formation on said conducting element that engages said insulating element, said formation being so proportioned as to compensate for any slight variations in size of said insulating element to establish an air gap of predetermined length between said plate and said element when juxtaposed.

25 9. As a new article of manufacture a protector element adapted to cooperate with a ground plate, comprising as a unitary structure a U-shaped conducting element having two serrated active extremities and an insulating element set in definite relationship to establish an air gap of predetermined length between said plate and element when juxtaposed, said insulating element having holes and said conducting element having fingers forced into said holes whereby the two parts are fixedly held together.

10. As a new article of manufacture a protector element adapted to cooperate with a ground plate, comprising as a unitary structure a U-shaped conducting element having two serrated active extremities and an insulating element set in definite relationship to establish an air gap of predetermined length between said plate and element when juxtaposed, said conducting element at its active extremity being spaced from said insulating element to prevent the accumulation of foreign matter at said active extremity, said insulating element having holes and said conducting element having fingers

forced into said holes whereby the two parts are fixedly held together.

11. As a new article of manufacture a protector element adapted to cooperate with a ground plate, comprising as a unitary structure a conducting element and an insulating element, said elements having means whereby they are secured together, and one of said elements having means provided thereon engaging the other of said elements so proportioned as to compensate for any slight variations in size of said other element to establish an air gap of predetermined length between said ground plate and conducting element when juxtaposed.

12. A protector of the character described comprising a pair of substantially parallel metallic fingers, and a pair of arrester elements removably held in cooperative relationship by said fingers, said fingers extending lengthwise of said elements and one of said arrester elements consisting of a piece of metal having a serrated edge.

13. In a device of the character described, an arrester element, means for demountably carrying said arrester element and means for preventing displacement of said arrester element transverse to its length, said arrester element comprising a conducting element having a serrated edge portion, and means for insulatingly supporting said conducting element, the serrated edge of said element being laterally spaced from said supporting means, said conducting element embracing said supporting means, and being provided with means engaging said supporting means for holding said conducting element and supporting means in definite relationship.

14. A protector comprising a ground element, a U-shaped metallic element having serrations formed along its edges, and an insulating element positioned between the legs of said U-shaped element and maintaining said serrated edges in definite relationship with said ground element, the legs of said U-shaped element being spaced from the sides of said insulating element.

In witness whereof, I hereunto subscribe my name this 30th day of April, A. D., 1919.

WALLACE L. COOK.
